COOLING PANEL FOR A TRANSFORMER OR SIMILAR ARTICLE

Harold E. Hicks, Kirkwood, Mo., assignor to Nooter
Corporation, St. Louis, Mo., a corporation of Missouri

Filed July 21, 1966, Ser. No. 3,163

Term of patent 14 years

(Cl. D81—21)

FIG.1

FIG.2

FIG.3

FIG. 1 is a front elevational view of a cooling panel for a transformer or similar article showing my new design,

FIG. 2 is a side elevational view thereof,
FIG. 3 is a top plan view thereof,

FIG. 4 is a perspective view of the back side of the panel shown in FIG. 1 and shows a plurality of panels formed into a transformer cooling assembly with the inlet and return conduits shown in broken lines and only one of the cooling panels shown in full lines,

FIG. 5 is a fragmentary sectional view taken along line 5-5 of FIG. 4.

The essential features of my design reside in the portion shown in solid lines. The cooling panel has been shown broken away to indicate indeterminate length.

I claim:

The ornamental design for a cooling panel for a transformer or similar article, substantially as shown and described.
